UNITED STATES PATENT OFFICE.

PAUL E. LUETHJOHN, OF CLEVELAND, OHIO.

FLOOR SCRAPER OR CLEANER.

1,156,790.

Specification of Letters Patent. Patented Oct. 12, 1915.

Application filed December 1, 1913. Serial No. 804,129.

To all whom it may concern:

Be it known that I, PAUL E. LUETHJOHN, citizen of the United States, residing at Cleveland, in the county of Cuyahoga and State of Ohio, have invented certain new and useful Improvements in Floor Scrapers or Cleaners, of which the following is a specification.

My invention relates to new and useful improvements in scrapers and more particularly to scrapers for cleaning the runways of poultry houses, barns and the like, the object of my invention being the provision of a scraper which will thoroughly remove all waste matter from the runways and which is further adapted to spread sand, saw-dust or the like over the surface scraped.

A further object of my invention is to provide the scraper with a floor engaging blade or knife which is swingingly mounted and to provide means for varying the force with which the blade or knife will engage the floor being scraped.

A further object of my invention is to provide a winding drum and endless cable passing about the drum and pulleys and connected to the scraper, whereby rotation of the drum in one direction will advance the scraper and rotation of the drum in the opposite direction return the scraper to normal position.

In this connection, a still further object of my invention is to so attach the actuating cable to the scraper that upon return movement of the scraper, the cable will act to automatically raise the blade or knife of the scraper out of engagement with the floor.

My improved scraper is intended to occupy the entire width of the runway or surface being cleaned and for this reason I provide the body of the scraper with laterally directed rollers for engagement against the walls of the runway.

With these and other objects in view, my invention will be more fully described, illustrated in the accompanying drawing, and then specifically pointed out in the claims which are attached to and form a part of this application.

In the drawing: Figure 1 is a perspective view of my improved scraper; Fig. 2 is a fragmentary longitudinal sectional view; Fig. 3 is a top plan view of the actuating drum, the top of the housing being removed to fully disclose the drum and coöoperating mechanism.

Corresponding and like parts are referred to in the following description and indicated in all the views of the drawing by the same reference characters.

The body of my scraper consists of a substantially rectangular frame 10 including spaced side members 11 and 12 and a transversely extending forward brace 13. The side members are identical in construction and a description of one will therefore suffice for both. Each of these side members is preferably formed from a single piece of metal having its forward end bent upwardly as shown at 14 and provided intermediate its length and at its rear end with bearings 15 to receive the front and rear axles 16 and 17, these axles being secured against rotation in their bearings by set bolts 18, whereby the axles, together with the brace 13, serve to hold the side members of the frame in proper spaced relation to each other. Supporting wheels 19 are rotatably mounted upon these axles and are held against longitudinal movement thereon by means of L-shaped arms 20 preferably formed integrally with the side members 11 and engaging by their free ends against the inner edges of the wheels. These arms are so positioned with respect to the wheels as to serve as scrapers to remove any waste matter from the wheels. The side members of the frame immediately at the rear of each axle bearing are provided with outwardly directed, vertically spaced apart ears 21 to receive shafts 22 upon which are journaled rollers 23. The rollers project beyond the sides of the scraper proper and in use, engage against the walls of the runway in which the scraper is being employed to insure uniform movement of the scraper.

The forward cross brace 13 of the frame is provided adjacent its ends and at other suitable intervals with upwardly directed ears 24 to which are pivotally mounted the forward ends of rearwardly extending rods 25. These rods are provided intermediate their length with downwardly directed arms 26, which may or may not be integral with the rods, the lower ends of which are preferably inclined forwardly as shown at 27 to receive and support the blade or knife 28 of the scraper, the blade being secured to these extensions by rivets or other suitable fastening devices 29. The rods 25 at the rear of the arms 26 are connected and maintained in suitable spaced relation by a brace

bar 30 to which the rods are secured by clevis bolts 31. Slidably mounted upon the free ends of the rods 25 are weights 32 which may be secured in adjusted position 5 by set bolts 33 and which serve as a means for varying the force with which the scraper blade or knife engages the floor being scraped. The rods 25 are provided immediately at the rear of the brace rod 30 with 10 downwardly depending ears 34 to which are pivotally mounted prongs 35, the free ends of which drag the floor during forward movement of the scraper. At this point, it should be noted that if the scraper is drawn 15 rearwardly, these prongs will engage in the floor and serve to momentarily raise the rods 26 and consequently the scraper blade or knife.

The outermost of the rods 25 upon either 20 side are mounted exteriorly of the side members 11 of the frame but interiorly of the planes of the rollers 23 and carry vertically disposed shields 36, each preferably consisting of a single plate of sheet metal. These 25 shields serve to prevent any escape of waste matter past the ends of the blade or knife during operation of the scraper and also serve as runners to prevent undue tilting of the scraper as a whole should the blade become caught upon any object projecting 30 from the floor, such as a nail head or knot.

A substantially rectangular shaped trough 37 is supported by the side members of the frame between the front and rear axles, this 35 trough being provided with converging bottom walls 38 spaced apart at their lower edges to provide a narrow feed slot 39. The ends of this trough bear against the inner faces 40 of the side members of the frame and are provided with outwardly and downwardly directed extensions or lips 40 which engage over the side members of the frame and support the trough. In use, sand, saw-dust or other material is placed in the trough and feeds through the slot through vibration of the trough, due to movement of the scraper. 45

Mounted for turning movement upon the central portion of the forward axle 16, is a sleeve 41, the turning of which is limited by a set screw 42 extending through a slot 43 formed in the sleeve and threaded into the axle. This sleeve carries an integrally formed, radially extending cam 44 having a longitudinally grooved, arcuate cam face 45. 50 This cam is so proportioned that when swung to forward position, its cam face is spaced immediately below the brace 30 connecting the blade carrying rods 25 and when swung to rearward position, its cam face engages the bar 30 to raise the same and consequently to raise the scraper blade or knife. It will of course be understood that this scraper may be drawn back and forth along the runway in any suitable manner but I 55 prefer to operate it in the manner shown in

Figs. 1 and 3 of the drawing for the reason that such an arrangement permits the automatic raising of the scraper knife or blade during return movement of the scraper. The construction shown for operating the 70 scraper includes a housing 46 mounted at one end of the runway and provided with bearings for a shaft 47 carrying a winding drum 48 and spur gear 49. This spur gear meshes with a pinion 50 carried by a stub 75 shaft 51 also journaled in the housing and a hand crank 52 carried by this stub shaft serves as a means for manually operating the winding drum 48.

A pulley 53 is mounted in proper position 80 at the opposite end of the runway and a cable 54 is wound for a number of turns about the winding drum and passed about the pulley 53, being secured at its ends to opposite ends of the cam 44. Intermediate 85 portions of this cable may be passed under suitable guide pulleys 55 carried by a bracket 56, if desired.

Bars 57 are secured in the housing immediately in front and at the rear of the 90 winding drum 48 and are provided with spaced teeth 58, the ends of which lightly engage against the peripheral face of the winding drum and serve to maintain the various convolutions of the actuating cable 95 in proper spaced relation. These teeth are so formed that the cable is wound helically about the winding drum and they therefore, in connection with the drum, insure sufficient frictional engagement of the cable to 100 cause any turning of the winding drum to move the scraper.

In operation, assuming that the scraper is at that end of the runway adjacent the winding drum, the winding drum is so rotated as to draw the scraper toward the pulley 53. This rotation of the winding drum acts through the cable 54 to not only move the scraper, but to swing the cam 44 to raise the bar 30 and consequently the scraper 110 blade or knife. The engagement of the prongs 35 in the floor of the runway, as soon as the scraper starts to move, assists in this operation. During this movement of the scraper, sand, saw-dust or the like, is discharged from the trough 37 upon the 115 floor to cover the waste matter thereon. When the scraper has reached the farther end of the runway, the direction of rotation of the winding drum is reversed. This reverses the direction of movement of the cable 54 and causes reverse swinging of the cam 44 out of engagement with the bar 30 thereby permitting the scraper blade or 120 knife to swing into engagement with the floor, the prongs 35 then trailing behind. Upon return movement of the scraper, the blade engages the floor and collects all waste matter thereon, while sand or saw-dust is again distributed over the freshly cleaned 130

surface. It will be clear that by proper adjustment of the weights 32, the blade may be forced into any desired engagement with the floor, and that by proper adjustment of the width of the slot in the trough, any desired quantity of sand or saw-dust may be spread upon the floor.

5 I do not wish in any way to limit myself to the specific details of construction, illustrated in the drawing and described in the specification, as various minor changes, within the scope of the appended claims, may be made at any time, without in the slightest degree departing from the spirit 10 of my invention.

15 In order to prevent any escaping of waste over the upper edge of the blade or scraper 28, I provide a shield or apron 59, preferably formed of sheet metal and loosely secured to the blade supporting arms 26 by clevis bolts 60, enough freedom being allowed this apron to permit tilting of the blade in case the floor is uneven.

Having thus described the invention, what 25 is claimed as new is:

1. A scraper including a frame, rods 30 swingingly mounted upon the frame and extending rearwardly thereof, a scraper blade supported by said rods, and adjustable weights slidable upon the free ends of the rods.

2. A scraper including a wheeled frame, rods swingingly mounted in the frame, a scraper blade supported by the intermediate 35 portions of said rods and downwardly depending prongs swingingly mounted upon the rods at the rear of the scraper blade.

3. A scraper including a wheeled frame, 40 a scraper blade swingingly mounted on the frame, and a trough carried by the frame and provided with a feed slot.

4. A scraper including a wheeled frame having spaced side members, a scraper 45 blade swingingly carried by the frame and a trough extending transversely of the frame between the side members and provided in its bottom with a longitudinal feed slot, said trough having outwardly and 50 downwardly directed lips at its ends engaging the side members of the frame to support the trough.

5. A scraper including a wheeled frame 55 adapted for forward and rearward movement, a scraper blade swingingly carried by the frame, means for moving the frame forwardly or backwardly, and means independent of said means for automatically raising the blade upon rearward movement 60 of the frame.

6. A floor scraping device including a winding drum, a pulley spaced from the winding drum; a wheeled scraper frame, a swingingly mounted cam member carried by 65 the frame, a cable wound about the wind-

ing drum and connected by one end to one end of the cam member and having its opposite end passed about the pulley and connected to the opposite end of the cam member, a scraper blade, and means swingingly supporting the scraper blade upon the frame, said means being engageable by the cam member.

7. A scraper including a frame, a scraper blade swingingly carried by the frame, a cam member carried by the frame and movable into position to raise the scraper blade, a winding drum and an actuating cable passed about the winding drum and connected by its ends to opposite ends of the cam member, whereby movement of the frame by the cable will cause movement of the cam member.

8. A runway cleaning system including a pulley adapted to be mounted at one end of the runway, a manually rotatable drum adapted to be mounted at the opposite end of the runway, a scraper movable along the runway, and a cable, the intermediate portion of which is wound about the drum and passed about the pulley, the ends of the cable leading from the drum and pulley being connected to the scraper, and means for maintaining the cable windings about the drum in proper position.

9. A scraper including a frame, a scraper blade carried by the frame, means for raising and lowering the scraper blade, and a trough carried by the frame at the rear of the blade and provided with a feed slot.

10. A scraper including a wheeled frame adapted for forward and rearward movement, a scraper blade swingingly carried by the frame, means for moving the frame forwardly or backwardly, means independent of said means for automatically raising the blade upon rearward movement of the frame, and additional means dependent upon the frame moving means for automatically raising the blade upon rearward movement of the frame.

11. A floor scraping device including a scraper frame, a swingingly mounted scraper blade carried by the frame, a swingingly mounted cam member carried by the frame and movable to raise and lower the blade, and means for moving the frame forwardly or rearwardly, said means being adapted to operate the cam member upon rearward movement of the frame to raise the scraper blade.

12. A floor scraping device including a scraper frame, a swingingly mounted scraper blade carried by the frame, a swingingly mounted cam member carried by the frame and movable to raise and lower the blade, and means for moving the frame forwardly or rearwardly, said means being adapted to operate the cam member upon rearward movement of the frame to raise the scraper blade.

blade and including a spaced winding drum and pulley, and a cable passed about the drum and pulley and secured at its ends to the cam member.

- 5 13. A scraper including a frame, rods swingingly mounted on the frame, a scraper blade supported by the intermediate portions of the rods, downwardly depending prongs swingingly mounted upon the 10 rods at the rear of the scraper blade, and

adjustable means carried by the rods for varying the downward pressure of the blade.

In testimony whereof I affix my signature in presence of two witnesses.
